(57) **CLAIM**

The ornamental design for a foldable chair as shown and described.

DESCRIPTION

FIG. 1 is a top, left perspective view of a foldable chair in accordance with a first embodiment of the Design shown in an assembled and unfolded position;

FIG. 2 is a top view of the foldable chair of FIG. 1;

FIG. 3 is a left side view of the foldable chair of FIG. 1;

FIG. 4 is a right side view of the foldable chair of FIG. 1;

FIG. 5 is a front view of the foldable chair of FIG. 1;

FIG. 6 is a rear view of the foldable chair of FIG. 1;

FIG. 7 is a top, left perspective view of a foldable chair in accordance with a first embodiment of the Design of FIG. 1 shown in a disassembled and folded position;

FIG. 8 is a top view of the foldable chair of FIG. 7;

FIG. 9 is a left side view of the foldable chair of FIG. 7;

FIG. 10 is a right side view of the foldable chair of FIG. 7;

FIG. 11 is a front view of the foldable chair of FIG. 7;

FIG. 12 is a rear view of the foldable chair of FIG. 7;

FIG. 13 is a top, left perspective view of a foldable chair in accordance with a second embodiment of the Design shown in an assembled and unfolded position;

FIG. 14 is a top view of the foldable chair of FIG. 13;

FIG. 15 is a left side view of the foldable chair of FIG. 13;

FIG. 16 is a right side view of the foldable chair of FIG. 13;

FIG. 17 is a front view of the foldable chair of FIG. 13;

FIG. 18 is a rear view of the foldable chair of FIG. 13;

FIG. 19 is a top, left perspective view of a foldable chair in accordance with a second embodiment of the Design of FIG. 13 shown in a disassembled and folded position;

FIG. 20 is a top view of the foldable chair of FIG. 19;

FIG. 21 is a left side view of the foldable chair of FIG. 19;

FIG. 22 is a right side view of the foldable chair of FIG. 19;

FIG. 23 is a front view of the foldable chair of FIG. 19; and,

FIG. 24 is a rear view of the foldable chair of FIG. 19.
